Ho Fletcher, of Providence, R. I.

assigned to

The Fletcher Manufacturing Company

Letters Patent No 2335 - Dated Jan 12, 1866.

Design for a Trade Mark.

The schedule referred to in these Letters Patent and making part of the same.

To all whom it may concern:

Be it known that A. Henry Fletcher of the city and County of Providence in the State of Rhode Island doth
hereby originate and design a new design for
a trade mark of which the following is a full, clear and
exact description, reference being had to the accompanying
specimens making part of this specification.

The design is intended for a trade mark to des-
ignate packages of Boot and Shoe Lacing.

It consists of a label or ticket of convenient size
to be pasted upon the package of which it is descript-
ive, having a surrounding border ~~representing~~
the variety of lacing which the package contains,
disposed in a rectangular form and so as to
show at each corner the pointed tags ~~at~~ with
which the lacing are tipped.

The space within the border can be filled with
the description of the size of lacing, the quantity
in the package and the name of the manufacturer.

What I claim as my invention and desire to
secure by Letters Patent, is

The design for a trade mark herein set forth and
shown.
